UNITED STATES PATENT OFFICE

95,949

DESIGN FOR AN ICE-CUBE SPOON

Milton S. Dunkelberger, Dayton, Ohio

Application March 16, 1935, Serial No. 55,903

Term of patent 7 years

To all whom it may concern:

Be it known that I, Milton S. Dunkelberger, a citizen of the United States, residing in the city of Dayton, in the county of Montgomery State of Ohio, have invented a new, original, and ornamental Design for an Ice-Cube Spoon, of which the following is a specification, reference being had to the accompanying drawing, forming part hereof.

The figure is a perspective view of an ice-cube spoon, showing my new design.

I claim:

The ornamental design for an ice-cube spoon, as shown.

MILTON S. DUNKELBERGER.
